UNITED STATES PATENT OFFICE

2,540,676

ACCUMULATOR

Edward D. Johnson, St. Louis, Mo., and Carl F. Wall, Marion, Ill., assignors to Wagner Electric Corporation, St. Louis, Mo., a corporation of Delaware

Application April 26, 1947, Serial No. 744,140

8 Claims. (Cl. 138—30)

1

Our invention relates to devices commonly referred to as "accumulators" for storing fluid under pressure for the operation of vehicle brakes and other devices and in its more specific aspects is directed to an accumulator embodying a plurality of bags containing a compressible medium, such as air or an inert gas, and by means of which pressure is maintained on the operating fluid in the accumulator.

One of the objects of our invention is to so construct the bags of the accumulator and associate them with the containing walls of the accumulator unit, that when fluid to be stored under pressure is forced into the unit, a uniform invagination of the bags will occur and there will be no entrapment of fluid between a portion of the walls of the bags and a wall of the containing unit either during the storing or discharging of the operating fluid.

Another object is to provide an accumulator unit embodying two bags or bladders, the closed ends of which, when the bladders are charged with the compressible medium and the unit is not charged with operating fluid, engage each other along approximately the center line of the accumulator unit and at which line a narrow circumferential slot is provided for the delivery and discharge of the operating fluid. The advantages of the construction just indicated will be more fully pointed out in the following description.

The drawing shows a vertical sectional view of an accumulator unit which comprises a cylindrical casing consisting of two identical sections 1 and 2 and a ring 3 which ring secures said sections together with their adjacent ends spaced apart whereby a circumferential narrow slot 4 is formed through which operating pressure fluid may be forced into the casing from the circumferential groove 5 formed on the inner face of the connecting ring 3. By means of an inlet fitting, conduit 6 for supplying operating pressure fluid is placed in communication with groove 5 and slot 4.

In each casing section is positioned a bag or bladder 7 made of flexible material having a normal shape as shown in the drawing except that the normal diameter of each bag is slightly larger than the interior diameter of the casing section in which it is contained whereby when installed in position the parts of the bag bearing on the wall of the container are maintained in slight pressure engagement therewith by reason of the resilience of the bag material. The outer ends of the bags are each provided with a closure located in this reduced portion. Each closure comprises a disc 8 and a plate 9 between the parts of which

2

the bead 10 around the bag opening is clamped. These closure elements are clamped together by fittings 12 and are retained in position by caps 13. A fluid seal 11 forms a fluid-tight connection between the periphery of plate 9 and the inner wall of the end of the casing section.

The fittings 12 in the bag closures are connected together by conduits 14 and 15 through an inlet valve 16 for the compressible fluid medium to be supplied to the interior of the bags, the bag chambers being interconnected through the conduits so that equal pressures are developed in the bags when charging them through valve 16. The normal position of the closed ends 15 or bottom walls of the bags, when no operating fluid is contained in the accumulator, is that shown in the drawing. In other words, the meeting line of the outer surfaces of these closed ends is normally substantially in alignment with slot 4. This slot is so narrow that under maximum pressure of the compressible fluid medium contained in the bags, the bag material will not be extruded into the slot even though a portion thereof should at any time lie across a part of the slot.

When operating fluid is forced into the accumulator through conduit 6, circumferential groove 5, and slot 4, the air or other gaseous content of the bags is compressed, the bottom walls 30 of the bags being flexed as indicated in the drawing.

By the use of two bags in lieu of a single bag in an accumulator unit of a particular capacity relatively small peripheral areas of each bag will be withdrawn from contact with the casing walls when the unit is fully charged with operating fluid and, therefore, the likelihood of entrapment of fluid in a localized area between the bag and container wall is very greatly decreased; and in a two bag structure with a peripheral supply and discharge slot for the operating fluid located at the center of the unit no special means is required to prevent entire blocking of the discharge for the operating fluid by the bag material under any operative condition.

Having fully described our invention, that which we claim as novel and desire to protect by Letters Patent of the United States is:

1. A pressure accumulator comprising a casing having oppositely disposed openings, two flexible bags in the casing for receiving gas under pressure, each bag having an inlet end secured in pressure-tight relation with the inner surface of the casing at one of said openings, the two bags being shaped so as to substantially fill the space

in the casing when under zero pressure conditions, and means for introducing pressure fluid into the casing at a point between said openings.

2. A pressure accumulator comprising a casing and two flexible bags therein for receiving a compressible medium, each of the bags having an opening therein through which fluid passes when entering or leaving the bags, said bags having their major portions lying in contact with the inner surface of the casing and having bottom walls positioned adjacent each other when the casing contains no charge of pressure fluid, and means including a circumferential slot in the casing through which to introduce pressure fluid into said casing at a point adjacent said last mentioned position of said bottom walls.

3. A pressure accumulator comprising a casing and two bags of resilient material therein for receiving a compressible medium, said bags having major portions of their surfaces in pressure contact with the interior surface of the casing and having bottom walls facing each other and located approximately at the center of the casing when the casing contains no charge of pressure fluid, means for charging the bags at equal pressures with a compressible medium, and means including a circumferentially disposed slot in said casing through which to introduce pressure fluid into said casing at its central portion.

4. A pressure accumulator comprising a casing having a circumferentially disposed slot through which to introduce pressure fluid into said casing at its central portion, two bags made of a resilient material in said casing for receiving a pressure fluid and having bottom walls, a fluid under pressure to be introduced into said bags from an external source, said bags under conditions of zero pressure having major portions of their surfaces in pressure contact with the interior surface of the casing and having their bottom walls facing each other and located approximately at the center of the casing when the casing contains no pressure fluid, a second pressure fluid to be introduced in said casing through said slot, and at least one of said pressure fluids being capable of occupying a space inversely proportional in volume to the pressure applied thereto.

5. A pressure accumulator comprising a pair of cylindrical members, each member having openings at each end thereof, means for connecting one end of one member to an end of the other member to form a casing provided with a circumferential slot between the members and so that the casing is open at its opposite ends, two flexible bags in said casing each having an open end for receiving a compressible medium, each of said open ends being secured in pressure-tight relation with the inner surface of the casing at

one of said openings, and means for introducing pressure fluid into the casing through said slot.

6. A pressure accumulator comprising a pair of coaxially oriented cylindrical members, each member having openings at each end thereof, a ring provided with an internal circumscribing groove and fitted around and joined in pressure-tight relationship to the adjacently disposed ends of said members so as to form a single open ended casing and assembled so as to provide a circumferential slot between the cylindrical members, said slot aligned with said groove to place same in communication with the interior of said casing, two flexible bags in said casing for receiving a fluid medium and each having an open end and a bottom wall, each of said ends being secured in pressure-tight relation with the inner surface of the casing at one of its openings and with the bottom walls adjacent to each other and in substantial alignment with said slot, and means for delivering pressure fluid into said casing through said slot to compress the fluid medium in said bags.

7. A pressure accumulator comprising a casing of circular cross-section having openings at opposite ends and provided with a narrow circumferential slot between its ends and formed in the inner surface of the casing, two flexible bags in said casing each having an open end for receiving a compressible medium, each of said open ends being secured in pressure-tight relation with the inner surface of the casing at one of said openings; and means for introducing pressure fluid into the casing through said slot.

8. A pressure accumulator comprising a casing of circular cross-section having openings at opposite ends and provided with a narrow internal circumferential slot, two flexible bags in said casing each having an open end for receiving a compressible medium, each of said open ends being secured in pressure-tight relation with the inner surface of said casing at said openings, means circumscribing said casing so constructed and arranged with respect to said casing as to form a circumferential fluid passageway in communication with said narrow circumferential slot; and means for introducing pressure fluid into said passageway.
